DESIGN FOR AN ELECTRIC IRON HANDLE

Dale C. Gerber, North Canton, Ohio, assignor to
The Hoover Company, North Canton, Ohio, a
corporation of Ohio

Application April 20, 1948, Serial No. 145,858

Term of patent 14 years

(Cl. D49—6)

To all whom it may concern:

Be it known that I, Dale C. Gerber, a citizen of the United States, residing at North Canton, in the county of Stark, and State of Ohio, have invented a new, original, and ornamental Design for an Electric Iron Handle, of which the following is a specification, reference being had to the accompanying drawing, forming a part thereof.

In the drawing:

Figure 1 is a top plan view of an electric iron handle showing my new design; and

Figure 2 is a side elevational view of the same.

I claim:

The ornamental design for an electric iron handle, substantially as shown.

DALE C. GERBER.
